UNITED STATES PATENT OFFICE

2,494,654

BOILER

Edwin A. Glynn, Lodi, Calif., assignor to Super Mold Corporation of California, Lodi, Calif., a corporation of California

Application September 7, 1948, Serial No. 48,072

11 Claims. (Cl. 219—39)

1

This invention is directed to, and it is an object to provide, a novel, small-type steam boiler; the boiler being a compact, unitary, prefabricated structure especially designed for use to supply steam to shop equipment, such as tire tread vulcanizing machines or the like.

Another object of the invention is to provide a boiler which includes a novel structure to house and support the water chamber of the device in insulated relation to the atmosphere; said chamber being of an improved design having a high safety factor.

A further object of the invention is to provide a relatively small, unitary boiler which is designed for ease and economy of manufacture on a production basis; the device including a minimum of parts, and these being capable of ready manufacture and assembly.

An additional object of the invention is to provide a novel, electrically heated boiler.

It is also an object to provide a boiler which is of relatively light weight with respect to its capacity.

A further object of the invention is to provide a practical and reliable boiler, and one which will be exceedingly effective for the purpose for which it is designed.

These objects are accomplished by means of such structure and relative arrangement of parts as will fully appear by a perusal of the following specification and claims.

In the drawings:

Fig. 1 is a sectional elevation of the boiler.

Fig. 2 is an end elevation, with the protector box removed, at the end from which the electric terminals project.

Fig. 3 is a cross section on line 3—3 of Fig. 1.

Referring now more particularly to the characters of reference on the drawings, the novel boiler comprises a pair of spaced, upstanding end walls or plates 1 and 2 disposed in parallel facing relation. At their lower ends the end walls 1 and 2 are formed with out-turned flanges 3 formed with openings 4, by means of which securing elements may attach said flanges to the floor.

On their adjacent faces, and in matching relation, the end walls 1 and 2 carry annular, inwardly projecting supporting flanges 5, and a tubular shell or jacket 6 extends full length between the end walls 1 and 2, with said annular supporting flanges 5 projecting into opposite ends of said jacket. The jacket 6 is connected to the flanges 5 by sheet metal screws 7, or the like.

A horizontally elongated, cylindrical water

chamber, indicated generally at 8, is disposed within the enclosure formed by the end walls 1 and 2, and the jacket 6; said chamber 8 being spaced, in said enclosure, from said parts, and such space being filled with an insulation material 9.

The horizontally elongated, cylindrical water chamber 8 comprises a pair of cast steel, domed heads 10 and 11 axially spaced apart and opening toward each other. Adjacent ends of the heads 10 and 11 are annularly grooved, as at 12, and a tubular body, preferably of heavy-duty sheet metal, extends between the heads 10 and 11; the ends of said body 13 engaging in the annular grooves 12, and being welded therein, as at 14.

To assure of rigidity of the chamber 8 within the enclosure formed by the end walls 1 and 2, and the jacket 6, the heads 10 and 11 are formed, 20 on the outside, with integral, transversely spaced feet 15 which project toward, and abut, the adjacent end wall 1 or 2 in matching relation; such feet 15 being attached to the corresponding end wall by cap screws 16. In this manner, the chamber 8 is always maintained in a fixed, predetermined position.

The tubular body 13, of the chamber 8, is provided, top and bottom, with fittings 17 which extend through the insulation material 9 and 30 jacket 6 for attachment of the exterior parts conventional to boilers; for example, a pressure relief valve 18; a pressure gauge 19; and flow fittings 20.

At opposite ends the heads 10 and 11 are formed with integral connection bosses; the bosses on the 35 head 10 being indicated at 21 and 22; there being a plurality of the latter. The head 11 includes a single connection boss 23. The connection bosses 21, 22, and 23 project from the heads to the corresponding end wall.

40 A thermo-well 24 is threaded into the connection boss 21, while screw plugs 25 are threaded into the bosses 22; said plugs 25 having electric heating elements 26, of "Calrod" type, projecting into the chamber 8 therefrom. The electric 45 heating elements 26 are elongated, and extend from the plugs 25 substantially full length of the chamber 8 generally in the lower half thereof.

The electric terminals 27 for the heating elements 26 project outwardly from the screw plugs 50 25.

A water glass assembly, indicated generally at 28, connects between the boss 23 and one of the fittings 17 at the top of the chamber 8.

The end wall 1 is extended some distance above the top of the jacket 6 in the form of a vertical

panel 29, and said panel, together with the terminals 27 which project from the screw plugs 25, are normally enclosed, in safety relation, within a protector box 30, removably attached to the end wall 1 and panel 29 by flanges 31 and securing screws 32.

The electric wiring for the boiler leads into the protector box 30 through a fitting 33 at the top of the panel 29; there being a magnetic contactor, indicated diagrammatically at 34, included in the wiring circuit and mounted on the panel 29 within the box 30. The wiring system of the boiler has been omitted for the sake of clarity, and the details of such system form no part of the present invention; it sufficing to state that the magnetic contactor 34 acts to control the supply of electric current fed to the heating elements 27.

The structure described provides a small-size, efficient, relatively high-capacity boiler, whose compact unitary arrangement makes it very desirable for use to supply steam to shop equipment, such as tire tread vulcanizing machines or the like. The boiler is designed with a view towards simplicity and economy of manufacture; a substantial number of the parts being capable of fabrication from sheet metal.

The boiler is practical and reliable in operation, and it has a high safety factor.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A unitary boiler comprising a pair of upstanding end plates disposed in facing, spaced-apart relation, annular supporting flanges on the end plates projecting toward each other in alignment, a tubular jacket extending between the end plates, the annular supporting flanges and adjacent ends of the jacket telescoping in close fitting relation, means securing the same together, a water chamber in spaced relation within the enclosure formed by the end plates and jacket, and insulation between the chamber and said enclosure.

2. A boiler, as in claim 1, in which the end plates project below the jacket, and floor engaging members on the lower edges of said end plates.

3. A boiler, as in claim 1, in which one end plate extends above the jacket as a mounting panel for boiler control means.

4. A unitary boiler comprising a pair of upstanding end plates disposed in facing, spaced-apart relation, a tubular jacket extending between the end plates, means securing the jacket at its ends to the end plates, a water chamber in spaced relation within the enclosure formed by the end plates and jacket, and insulation between the chamber and said enclosure; the end plates extending below the jacket as boiler supports.

5. A unitary boiler comprising a pair of upstanding end plates disposed in facing, spaced-

apart relation, a tubular jacket extending between the end plates, means securing the jacket at its ends to the end plates, a water chamber in spaced relation within the enclosure formed by the end plates and jacket, and insulation between the chamber and said enclosure; the end plates extending below the jacket as boiler supports, and floor flanges on the lower edges of said plates.

10 6. A unitary boiler comprising a pair of upstanding end plates disposed in facing, spaced-apart relation, a tubular jacket extending between the end plates, means securing the jacket at its ends to the end plates, a water chamber in spaced relation within the enclosure formed by the end plates and jacket, and insulation between the chamber and said enclosure; one end plate extending above the jacket as a panel.

20 7. A unitary boiler comprising a pair of upstanding end plates disposed in facing, spaced-apart relation, a tubular jacket extending between the end plates, means securing the jacket at its ends to the end plates, a water chamber in spaced relation within the enclosure formed by the end plates and jacket, and insulation between the chamber and said enclosure; one end plate extending above the jacket as a panel, and a protector box over said panel and an adjacent part of said one end plate.

30 8. A boiler, as in claim 7, in which the boiler is electrically actuated; there being terminals projecting from said one end plate into said protector box.

35 9. A unitary boiler comprising a pair of upstanding end plates disposed in facing, spaced-apart relation, a tubular jacket extending between the end plates, means securing the jacket at its ends to the end plates, a water chamber in spaced relation within the enclosure formed by the end plates and jacket, and insulation between the chamber and said enclosure; there being attachment feet on opposite ends of the chamber extending to, and secured in connection with, adjacent end plates.

40 45 10. A unitary boiler comprising an outer shell which includes end plates, a water chamber disposed within and spaced from the outer shell including the end plates, such water chamber consisting of cast steel end heads, a cylindrical intermediate member extending between and welded to the end heads, the end heads including feet cast integral therewith and projecting to the end plates of the outer shell, means connecting the feet to the end plates, insulation material between the water chamber and the outer shell, and heating elements supported in one of the end heads and enclosed within the water chamber.

50 55 11. A boiler as in claim 10 including connection bosses cast integral with the end heads and projecting to the end plates, the heating elements including screw plugs threaded into certain of said bosses.

EDWIN A. GLYNN.
